UNITED STATES PATENT OFFICE.

PAUL H. ZIMMER, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLING DEVICE.

1,086,431.

Specification of Letters Patent. Patented Feb. 10, 1914.

Application filed August 3, 1911, Serial No. 642,109. Renewed June 30, 1913. Serial No. 776,737.

To all whom it may concern:

Be it known that I, PAUL H. ZIMMER, a citizen of the United States, residing at Milwaukee, in the county of Milwaukee and State of Wisconsin, have invented new and useful Improvements in Controlling Devices, of which the following is a full, clear, concise, and exact description, reference being had to the accompanying drawing, forming 10 a part of this specification.

My invention relates to improvements in controlling devices.

It is one of the objects of my invention to provide a simple, efficient and durable device for controlling a plurality of circuits and by means of which the circuits may be completed or interrupted in a predetermined sequence.

Various other objects and advantages of 20 my invention will be hereinafter set forth.

My invention is particularly applicable to the control of electric motors, especially for starting and accelerating the same. It is however, susceptible of use in various other 25 relations and for various different purposes.

For the purpose of clearly and fully setting forth the nature and characteristic features of my invention I shall describe the 30 motor controller illustrated in the accompanying drawing which embodies my invention in one form. It should be understood however, that my invention is not limited to the particular embodiment thereof illustrated but is susceptible of various modifications.

In the accompanying drawings: Figure 1 is a perspective view of the controller. Fig. 2 is a perspective view of parts shown in Fig. 1, certain of the parts being shown in 40 section. Fig. 3 is a detail view of one of the contact members and a portion of its supporting member, and Fig. 4 is a diagrammatic view showing one form of connections between the controller and an electric motor 45 whereby the controller will serve as an automatic starting device.

The various parts of the controller are mounted upon an insulating panel 1. The controller includes a series of switch members 2, 3, 4 and 5, an operating solenoid 6 therefor, and a main line switch 7. In the controller illustrated the switches 2 to 5 serve to control a starting resistance which may be mounted in the box 8 to which the 55 panel 1 is attached.

In practice the switch members 2 to 5 may be of any preferred construction. As illustrated each comprises a sheet metal strip having its longitudinal edges upturned for strengthening purposes. Each contact member is provided at its upper extremity with a contact tip 10 which may be secured thereto in any suitable manner. The contact tips 10 are preferably provided with curved active faces as illustrated. The switch members 2, 3, 4 and 5 are provided with co-operating stationary contacts 11, 12, 13, and 14 respectively. In practice the stationary contacts may be of any preferred type. The switch members are all mounted upon a common supporting and operating member 15. The member 15 is provided at opposite ends with co-axial trunnions 16 and 17 having bearings in blocks 18 and 19 respectively secured to the panel 1. The member 15 is provided with downwardly extending lugs 20, 21, 22 and 23 one for each of the switch members. Each of these lugs is provided adjacent to its lower extremity with an outwardly projecting pin 24 fitting into a recess or orifice in the lower extremity of its corresponding switch member to support the same. The recesses or orifices in the switch members are preferably made of sufficient size to permit of a rocking movement of each of the same upon the rounded extremity 26 of its corresponding lug. For preventing lateral play of the switch members on their supporting pins, a second pin 27 is passed through each switch member and secured in any suitable manner to the supporting member 15. Upon each of the pins 27 is placed a spiral spring 28 interposed between the switch member and a cotter pin 29 passing through the outer extremity of the pin 27. The springs 28 thus tend to force the switch members inwardly or toward the supporting member. Upwardly extending lugs 20^a, 21^a, 22^a and 23^a are provided upon the member 15 to limit the inward movement of the switch members. The lugs on the member 15 are disposed at relatively different angles with the result that the switch members are all normally held at different distances from their respective stationary contacts. As illustrated, the angular positions of the switches is such that upon movement of the member 15 upon its trunnions, the switches 2, 3, 4 and 5 will engage their respective contacts successively in the order given and

will disengage their respective contacts in an inverse order. It will thus be seen that I have provided a very simple, efficient and reliable means for enabling the completion 5 or interruption of a plurality of circuits in any predetermined order or sequence, it being understood that in practice any number of switches may be employed and that they may be disposed at any desired angles relative to one another.

Assuming the supporting member for the switches to be of conducting material, it is apparent that said switches will all be electrically connected, and hence under such conditions would need but a single line connection. Such a connection may be conveniently made to the switch 5 from a suitable binding post 30 by a suitable flexible conductor 31. Of course the switches may be 15 made electrically independent if desired and each given a separate connection.

For facilitating the connection of the member 15 with the operating solenoid I have provided said member with a pair of lugs 32 and 33 between which is arranged an insulating link 34 connected thereto by a pin 35. The other end of this insulating link is connected by a pin 36 to an extension 37 of the plunger of the solenoid 6.

30 For a purpose hereinafter explained, I have mounted above the solenoid a switch 38 supported by a member 39 secured to the solenoid frame, said switch yieldingly engaging a contact post 40 secured to the panel 35 1. For operating this switch I have provided a projection 41 on the lug 32 of the member 15.

For retarding the operation of the solenoid and thereby insuring a definite time interval between the closure of successive switches, I have provided a dash pot 42 having its piston connected with the plunger of the solenoid. To enable a quick closure of the switch member 2, I preferably provide a 40 lost motion connection between the plunger of the solenoid and the piston of the dash pot whereby the piston of the dash pot will not be actuated until after the closure of the first switch. This lost motion may be 45 readily provided for in various different ways. As illustrated, I have shown the plunger of the solenoid as provided with an extension 43 projecting into a tubular rod 44 connected with the piston of the dash pot, 50 the members 43 and 44 being connected by a pin 45 passing through a slot 46 in the member 43. To insure a quick opening of the switch 38 I desire to free the solenoid of the 55 retarding effect of the dash pot as soon as the switch 5 has been actuated. This may be accomplished in various different ways as for instance by providing the dash pot with a by-pass 47 suitably located to allow a free in-rush of air into the dash pot, and 60 thus eliminate the retarding effect thereof as

soon as the solenoid plunger has reached the desired point in its movement.

The main line switch illustrated is of a conventional double pole type and accordingly needs no detail description. It is preferably positioned on the panel as illustrated, that is, alongside of the operating solenoid and beneath the switches 2 to 5, thereby utilizing what would otherwise be waste space upon the panel and giving a very compact arrangement of the parts. As illustrated, I have also provided upon the panel 70 1 in the space between the switch 7 and the switches 2 to 5 fuse devices 48 and 49.

I shall now describe the mode of operation 80 and functions of the various parts of the controller in connection with the circuit diagram shown in Fig. 4. In this view I have shown the device used for controlling a shunt wound motor 50 provided with an 85 armature A and a shunt field winding F. The switch 2 is utilized for controlling the continuity of the motor circuit, while the switches 3, 4 and 5 are utilized for controlling the resistance sections r , r' and r^2 in 90 series with the motor armature. The switch 38 is utilized for controlling a short circuit around a resistance R connected in series with the operating solenoid 6. For controlling the circuit of the solenoid 6 I have provided a single pole switch 51. Current is supplied from main lines 52 and 53 through the main line switch 7 and fuse devices 48 and 49. With the parts of the controller in the position illustrated, the motor circuit is 95 open. To start the motor it is only necessary to close the switch 51. This completes a circuit from main line 53 by conductor 54 through the switch 51 and winding of solenoid 6 by conductor 55 through switch 38 100 105 by conductors 56 and 57 to main line 52. The solenoid thereupon responds and rocks the member 15 to close the switches 2, 3, 4 and 5 successively in the manner hereinbefore set forth. Upon closure of the switch 2 which takes place very quickly owing to the lost motion between the solenoid plunger and the dash pot, circuit is closed through the motor armature and shunt field winding. The armature circuit extends from conductor 54 through 110 conductor 58 through the motor armature and through the resistances r^2 , r' and r by conductor 59 through switch 2 by conductor 60 to conductor 57. The shunt field circuit extends from conductor 54 through the shunt field winding to conductor 59. The motor thereupon starts but with all of 115 the starting resistances included in circuit. Continued operation of the shaft 15 closes the switches 3, 4 and 5 successively and these switches in closing short circuit the resistances r , r' and r^2 successively, thereby gradually bringing the motor up to normal speed, the duration of the accelerating period being 120 125 governed by the dash pot 42. As soon as

switch 5 is actuated the plunger of the dash pot passes the by-pass 47, thus eliminating the retarding action of the dash pot. The plunger of the solenoid thereupon continues 5 the operation of the member 15 to cause the lug 41 thereon to engage with and open the switch 38 with a quick action to interrupt the short circuit around the resistance R. The resistance R is thus thrown in series with the 10 winding of the solenoid to reduce the flow of current therethrough to an amount just sufficient to enable the solenoid to retain the switches in closed position. To stop the motor it is only necessary to open the switch 15 51 whereupon the solenoid 6 is deenergized, thereby permitting the switches 2 to 5 inclusive to return to open position, said switches being given an impetus toward open position by the springs 28 which are 20 maintained under tension while the switches are closed.

Having thus described my invention, what I claim as new and desire to obtain by Letters Patent is:

25 1. In combination, a rotatable bar, a plurality of contact members carried thereby and coöperating stationary contacts for said contact members, said bar upon rotation moving said contact members and insuring 30 engagement thereof with their respective stationary contacts in a definite sequence, the operation of each of said contact members being arrested by its engagement with its coöperating contact.

35 2. In combination, a rotatable bar, a plurality of contact members carried thereby and coöperating stationary contacts for said contact members, said bar upon rotation moving said contact members and insuring 40 engagement thereof with their respective stationary contacts in a definite sequence, the operation of each of said contact members being arrested by its engagement with its coöperating contact, and a solenoid for 45 rotating said bar.

3. In combination, a rotatable member, a plurality of contact members secured thereto to move therewith but adapted to have their operation arrested without arresting 50 the operation of said rotatable member, and coöperating stationary contacts for said contact members, the former arresting the operation of the latter, said rotatable member being operable to move said contact members 55 into and out of engagement with their respective stationary contacts and to insure engagement and disengagement thereof in a definite sequence.

4. In combination, a rotatable member, a 60 plurality of contact members secured thereto to move therewith but adapted to have their operation arrested without arresting the operation of said rotatable member, and coöperating stationary contacts for said contact members, the former arresting the op-

eration of the latter, said rotatable member being operable to move said contact members into and out of engagement with their respective stationary contacts and to insure engagement and disengagement thereof in a 70 definite sequence, and a solenoid for rotating said rotatable member.

5. In combination, a movable member, a plurality of rocking contact arms supported and operable by said member, each of said arms having a connection with said movable member permitting its operation to be arrested independently of said movable member, and stationary contacts to be engaged by said contact members, said movable member insuring engagement of said contact members with their respective stationary contacts in a definite sequence. 75

6. In combination, a movable member, a plurality of contact members carried by said movable member and having a rocking movement imparted thereto by said movable member, a resilient connection between each of said contact members and said movable member permitting the operation of the former to be arrested independently of the latter, and stationary contacts to be engaged by said contact members, said movable member insuring engagement of said contact members with their respective stationary contacts in a definite sequence. 80

7. In combination, a movable member, a plurality of contact members carried by said movable member and having a rocking movement imparted thereto by said movable member, a resilient connection between each of said contact members and said movable member permitting the operation of the former to be arrested independently of the latter, stationary contacts to be engaged by 100 said contact members, said movable member insuring engagement of said contact members with their respective stationary contacts in a definite sequence, and a solenoid for operating said movable member to move 105 all of said contact members into engagement with their respective stationary contacts and through said resilient connections to place each contact member under pressure during the operation of succeeding contact members. 110

8. In combination, a plurality of switch members and a common supporting member therefor, said switch members being yieldingly connected to said supporting member and being normally disposed in relatively different angular positions upon said operating member. 120

9. In combination, a plurality of switch members and a common supporting member therefor, pivotally mounted to actuate said switch members, said switch members being disposed in relatively different angular positions upon said operating member and yieldingly connected thereto. 125

10. In combination, a revolvably mounted elongated member and a plurality of contact arms mounted side by side upon said member transversely thereof and in relatively different angles thereon, each of said arms having a resilient connection with said member.
11. In combination, a revolvably mounted elongated member and a plurality of contact arms mounted side by side upon said member transversely thereof and at relatively different angles thereon, each of said arms having a substantially pivotal movement upon said member and being biased against such movement.
12. In combination, a revolvably mounted elongated member having a plurality of pairs of transversely extending lugs thereon, said lugs being disposed in relatively different angular positions upon said member and the lugs of each pair being substantially in longitudinal alinement, a plurality of contact members, each of said contact members being yieldingly secured against a pair of said lugs and one lug of each pair having a portion engaging with its corresponding contact member adjacent to its extremity to positively support the same but permitting a rocking movement of the contact member thereon.
13. In combination, a revolvably mounted elongated member, a plurality of pairs of lugs thereon extending transversely to the axis thereof, a plurality of contact members, a pin projecting from one of each pair of lugs and extending into one of said contact members to support the same and permit of a rocking movement of each contact member about the extremity of its supporting lug and a resilient connection between each of said contact members and said first mentioned member for holding the contact members in place.
14. In combination, a revolvably mounted elongated member, a plurality of pairs of lugs thereon extending transversely to the axis thereof, a plurality of contact members, a pin projecting from one of each pair of lugs and extending into one of said contact members to support the same and permit of a rocking movement of each contact member about the extremity of its supporting lug and a resilient connection between each of

said contact members and said first mentioned member for holding the contact members in place, each of said connections consisting of a pin connected to said first mentioned member and passing through the contact member and a spiral spring surrounding said pin and interposed between a stop on said pin and the contact member.

15. In combination, a rotatable bar, a plurality of contact members mounted thereon, a resilient connection between each of said contact members and said bar, coöperating stationary contacts for said contact members, said bar having parts normally holding said contact members in a relation to insure engagement thereof with their respective stationary contacts in a definite sequence and said bar when rotated moving all of said contacts simultaneously until the first of the same engages its respective contact, and thereafter moving the remaining contact members into engagement with their respective contacts and successively placing the same under tension.

16. In combination, a rotatable bar, a plurality of contact members mounted thereon, a resilient connection between each of said contact members and said bar, coöperating stationary contacts for said contact members, said bar having parts normally holding said contact members in a relation to insure engagement thereof with their respective stationary contacts in a definite sequence and said bar when rotated moving all of said contacts simultaneously until the first of the same engages its respective contact, and thereafter moving the remaining contact members into engagement with their respective contacts and successively placing the same under tension, and a solenoid for rotating said bar.

17. In combination, a pivoted member, a contact finger yieldingly secured against said pivoted member, and a pin on said pivoted member projecting into a recess in said finger contiguous to one extremity thereof.

In witness whereof, I have hereunto subscribed my name in the presence of two witnesses.

PAUL H. ZIMMER.
